(57) **CLAIM**

The ornamental design for an axe head, as shown and described.

DESCRIPTION

FIG. 1 is a first perspective view of an axe head showing a first embodiment of my new design; and,

FIG. 2 is a second perspective view of the axe head shown in FIG. 1.

The broken lines shown in the drawings represent portions of the axe head that form no part of the claimed design. The bottom view forms no part of the claimed design.

1 Claim, 2 Drawing Sheets

FIG. 1

FIG. 2
